EDWARD P. BAIRD, OF EVANSTON, ILLINOIS, ASSIGNOR TO FRED GERLACH, OF CHICAGO, ILLINOIS.

COIN-CONTROLLED LOCK.

1,149,990.

Specification of Letters Patent. Patented Aug. 10, 1915.

Application filed July 16, 1913. Serial No. 779,255.

To all whom it may concern:

Be it known that I, EDWARD P. BAIRD, a resident of Evanston, in the county of Cook and State of Illinois, have invented 5 certain new and useful Improvements in Coin-Controlled Locks, of which the following is a full, clear, and exact description.

The invention relates to coin-controlled locks.

10 The invention designs to provide an improved construction and operation of coin-controlled lock of that type in which deposit of a coin and the operation of a key are necessary to release the key and permit the 15 depositor to carry it away until such time as he may replace the key in the lock. This type of lock is used for coin-controlled lockers or closets for the use of which a service charge is made and in which a coin must be 20 deposited in order to release the key which is locked against removal when it unlocks the locker and until another coin is deposited.

25 The invention consists in the several novel features hereinafter set forth and more particularly defined by claims at the conclusion hereof.

In the drawings; Figure 1 is a perspective of the improved lock. Fig. 2 is a rear elevation, the parts being shown in position assumed when a coin is suspended in the lock, and the key has been withdrawn. Fig. 3 is a similar view, parts being removed, the mechanism being shown in position assumed 35 when the coin has been deposited, but before the key-lock has been operated. Fig. 4 is a side elevation. Fig. 5 is a section taken on line 5—5 of Fig. 2. Fig. 6 is a section taken on line 6—6 of Fig. 2. Fig. 7 is a section 40 taken on line 7—7 of Fig. 3. Fig. 8 is a section similar to Fig. 5, but showing the plates in normal position. Fig. 9 is a rear view, similar to Fig. 2, parts being removed, the locking devices for the supporting plate 45 being shown. Fig. 10, is a perspective of one of the channel bars showing the manner in which it is cut away to receive the locking plates. Figs. 11 and 12 are details showing the operation of the presser arm for the coin.

50 The lock is adapted to be mounted into a channel-bar 15 which forms a part of the frame-work of the locker, the front and a portion of one of the sides of the channel-bar being cut away to receive a plate 16 55 which serves as a mount or support for the coin-controlled locking-mechanism. The

front wall of plate 16 is provided with a pair of lugs 17 which are adapted to fit into the channel-bar and hold the lower portion of the plate in position therein. A top-flange 18 is formed on the plate and has a slot 19 for a latch 20 which is usually secured to a reciprocable bar 21. A side flange 22 is formed on the plate and a locking-bolt 23 for securing the locker-door 24 passes through said flange. In practice, the 60 lockers are usually arranged in tiers and a common locking bolt 21 serves for an entire vertical series or tier of locks. At times, it is desirable to change the locks around or to 65 substitute others therefor, and in some instances, where the depositor carries off the key for an excessive period, it is desirable to open the locker. By employing the bolt 21 and latches 20 which are suitably controlled by a master-lock, as well understood in the art, the plates 16 may be readily released. A spring strip 25 secured to the 70 inner face of flange 22 by a rivet 27, is 75 adapted to frictionally engage one of the side-flanges of the channel-bar 15, so that when bolt 21 is operated to release the coin-controlled locks, the latter will not fall out of the channel-bar. As a result of this 80 construction, the plate 16 may be swung outwardly from the channel-bar and then lugs 17 permit it to be lifted out of the bar. During placement or replacement of the 85 several plates, strips 25 serve to hold each plate in position until the locking-bar 21 is operated to lock all the plates or until the plates 90 are removed.

A key-lock of usual construction is secured to plate 16 by screws 30 and comprises a cylinder 31, a tumbler-barrel 32 having a key-slot 33 therein, all of which may be of usual construction. An arm 34 is secured to the tumbler-barrel and the latter is adapted to be rotated by a key 35 of the proper shape. The usual face-plate 36 is rotatable 95 with the key and tumbler-barrel, as well understood in the art. Arm 34 extends into a notch 37 in a slidable bolt 23 which is adapted to be projected into an opening in, and to lock the locker-door 24. As usual in key-locks of this type, the key cannot be withdrawn from the barrel except when bolt 23 is in locking position. Besides being guided in the flange 22 of the supporting-plate 16, bolt 23 is guided in a notch in a strip 44 which is riveted, as at 45, to the back of the plate 16. Coin-controlled mech-

anism serves to lock the key and barrel against rotation to shift bolt 23, and to control shift of the lock into its locking position. This mechanism comprises a pair of plates 39 and 40 which are connected to the face-plate 36 at opposite sides of its center, so that they will be shifted in opposite directions when the face-plate is rotated. Plate 39 is connected to plate 36 by a screw 41 at one side thereof and plate 40 is connected to face-plate 36 by a screw 42 at the opposite side. These screws extend through arcuate slots 43 in plate 16 which permit the screws to pass through plate 16 and to rotate with the face-plate. Plate 39 is formed with a stop-shoulder 46 which is adapted to engage a pin 47 which is fixed on the back of plate 16 and extends through a slot 48 in plate 40. This stop and pin serve to prevent sufficient turning of the key 35, barrel 32 and face-plate 36 to release the key until a coin has been deposited. Stop 46 is adapted to be shifted laterally by a deposited coin to clear pin 47, and release the plates for sufficient movement for the operation of bolt 23. Plate 39 is provided with a forwardly turned lip 49 which is adapted to engage a deposited coin and positively force it downwardly past an inclined 30 stop or cam 50 on one edge of plate 40.

An inclined coin-chute 52 is secured to the front of plate 16 so as to direct a coin downwardly and backwardly into the space between plates 39 and 40. The deposited coin will remain in angled position shown in Fig. 8, an opening 53 being cut in plate 39 to receive the lower segment of the inclined coin. A spring-strip 54 which is secured to plate 39, as at 55, has a forwardly turned terminal 56 which is adapted to press the lower segment of the coin, after initial movement of the plates, to cause the coin to be tilted into parallel relation with the faces of plates 39 and 40. Normally, this spring-45 arm 54 is held to clear the coin by a backwardly extending abutment 56^a on plate 40, which engages the terminal 57 of said spring-arm.

When a coin has been deposited between plates 39 and 40, and key 35 is turned, the coin, in being forced below or past the cam 50 by lip 49, will engage the inner edge 46' of plate 39 and force said plate laterally about its pivot-screw 41, which will cause shoulder 46 to clear stop-pin 47 and thus release the key-lock, so that the key can be turned into position to throw bolt 23 into locking-position and to permit the key 35 to be withdrawn. Stop 46 is normally disposed to permit initial movement of plates 39 and 40 and a slight turn of the key, independently of the coin. After initial movement of the plates, terminal 57 will pass above abutment 56^a and will release arm 54 so that it will exert pressure upon

the coin and cause it to be tilted into parallel relation with and against the back of plate 39 and into the path of lip 49, so that the coin will be positively shifted by said lip during rotation of key 35. When key 35 is rotated, bolt 23 is locked and the key 35 has been withdrawn, the coin will be held suspended and the parts will be in position indicated in Fig. 2. The coin will be held between edge 46' of plate 39 and a holding-edge 59 on plate 40. Plate 39 is provided with a notch 65 to receive pin 47 and permit said plate to swing laterally to hold the coin. Notch 65 is formed in edge 46' on plate 39 to permit said edge below said notch to hold the coin in curved seat 59 while the parts remain in position shown in Figs. 2 and 9. When plates 39 and 40 are restored to normal position, (Fig. 3), upward movement of plate 39 will cause the edge of the notch 65 to ride on pin 47 and move the holding-edge of plate 39 laterally to release the coin. When the key is replaced in the barrel, and the latter is turned to unlock bolt 23, plate 40 will be shifted into position shown in Fig. 3, and the coin which has been held in suspense will be released by edges 59 and 46'. As plate 39 is moved upwardly, the edge of notch 65 will move plate 39 laterally away from stop-pin 47 and holding-edge 59 to permit the coin to fall into a suitable receptacle. When a coin is held in suspense, as shown in Fig. 2, lip 49 on plate 39 will obstruct the passageway for the coins, so that a second coin cannot be deposited while the locker is in use.

A coil-spring 60 has one of its terminals connected to plate 39 as at 61, and its other terminal to plate 40, as at 62. This spring serves to hold plate 39 and parts thereon normally in position to cause abutment 46 to be in alignment with stop-pin 47 but permits plate 39 to yield laterally as a coin is forced downwardly by a lip 49.

The purpose of holding presser-arm 54 clear of the coin until after the plates have been shifted, is to leave the coin free, until manual force is applied thereto and then to apply pressure to move the upper segment of the coin into the path of lip 49. Lost-motion of the plates is necessary to permit initial shift of the coin to release the plates. Spring 60 is applied to both of the plates 39, 40 to hold them in normal position, and to restore them to such position when the key is inserted to release bolt 23. By employing a coil-spring between the plates, both will be effectively held in normal position to insure that they will be correctly positioned to receive a coin.

A flat spring 66 is secured to strip 44 and has its terminal formed to pass into a V-shaped notch 67 in bolt 23. This formation of the notch and spring, causes the spring to aid spring 60 in imparting the

final shift to the parts in restoring them to normal position in readiness to receive a coin.

The operation of the improved device will be as follows: Assuming the parts to be in normal position shown in Figs. 1 and 2, the key 35 will be held against withdrawal by the lock itself and the barrel will be locked against sufficient rotation to permit the key 10 to be withdrawn by co-action to stop 46 on plate 39 and pin 47. When a coin is deposited into chute 52, it will pass into position shown in Fig. 8. If key 35 is then turned, plates 39 and 40 will be moved in opposite directions and the initial movement will cause the coin-engaging cam 50 on one side of plate 40 to force the coin and plate 39 laterally, so stop 46 will clear pin 47 and permit further rotation of the key. When the 20 parts are thus released, key 35 can be rotated until the parts are in position shown in Fig. 2 and then the key can be withdrawn, bolt 23 being locked at that time. After initial movement of the plates in opposite directions, presser-arm 54 will press the lower segment of the coin into a flat-wise position between the plates (Fig. 5.), so that the upper segment of the coin will be firmly held in position to be shifted by 30 manual force applied through key 35, to operate lip 49 on plate 39 to positively shift the coin. At this time, the coin will be held suspended between edge 46' on plate 39 and edge 59 on plate 40. When the key 35 is 35 again inserted into the lock and turned to shift the parts to normal position, the coin will be released and the device will be in readiness for another operation by a coin. Turning of the key 35 to restore the parts 40 causes them to unlock bolt 23 and to be locked against operation by the key until another coin has been deposited. It also causes the plates to release the suspended coin as the edge of notch 65 of plate 39 45 riding on pin 47 forces said plate laterally.

The invention is not to be understood as restricted to the details set forth, since these may be modified within the scope of the appended claims without departing from the 50 spirit and scope of the invention.

Having thus described the invention, what I claim as new and desire to secure by Letters Patent, is:

1. In coin-controlled mechanism, the combination of a lock, coin-controlled mechanism for controlling the operation of said lock, comprising a pair of oppositely movable plates, means for directing a coin angularly to said members, and a presser movable to engage the coin to press it flat-wise into position between said members.

2. In coin-controlled mechanism, the com-

bination of a lock, coin-controlled mechanism for controlling the operation of said lock comprising a pair of oppositely-mov- 65 able members, means for directing a coin angularly to said members, a presser for engaging the coin to press it flat-wise into position between said members, and means for rendering the presser normally inopera- 70 tive until the members have been shifted.

3. In coin-controlled mechanism, the combination of a lock, coin-controlled mechanism for controlling the operation of said lock comprising a pair of oppositely-mov- 75 able plates, means for directing a coin angularly to said members, a presser for engaging the coin to press it flat-wise into position between said members, and means on one of the plates for rendering the 80 presser inoperative.

4. In coin-controlled mechanism, the combination of a lock, coin-controlled mechanism for controlling the operation of said lock comprising a pair of oppositely-mov- 85 able members, means for directing a coin angularly to said members, a presser for engaging the coin to press it flat-wise into position between said members, and means on one of the members for rendering the 90 presser normally inoperative until the members have been shifted, said members having lost-motion which permits initial movement thereof independently of the coin.

5. In coin controlled mechanism, the com- 95 bination of a key operated lock, a coin controlled mechanism for controlling the opera- 100 tion of said lock comprising a pair of oppo- sitely movable members between which a passage-way is formed for a coin, locking means for one of said members which mem- 105 ber is movable laterally to disengage there- from, and a coil spring having its ends re- spectively connected to said oppositely mov- ing members to draw them toward each other.

6. In coin-controlled mechanism, the combination of a key-operated lock, a coin-con- 110 trolled mechanism for controlling the opera- 115 tion of said lock comprising a pair of oppo- sitely movable members between which a passage-way is formed for a coin, one of said members being laterally movable, lock- ing-means for said laterally movable mem- ber, and a coil-spring having its ends re- spectively connected to said oppositely mov- ing members, and applied to permit the lateral movement of the one member, said members being connected to be shifted by said lock.

EDWARD P. BAIRD.
